UNITED STATES PATENT OFFICE

2,503,047

DEEP WELL DRILLING APPARATUS

James A. Holcomb, Borger, Tex.

Application June 4, 1947, Serial No. 752,515

6 Claims. (CL 255-4)

1.

This invention relates to new and useful improvements in deep well drilling apparatus and the primary object of the present invention is to provide a device for imparting rotary motion to drill bits without the necessity of motor means.

Another important object of the present invention is to provide an attachment for deep well drills including novel and improved rotary means that increases the rotary motion of the drill bit as fluid is forced through the pipe to impinge the rotary means.

A further object of the present invention is to provide a device for imparting a rotary motion to drill bits that is quickly and readily applied to or removed from drill pipes of various sizes.

A still further aim is to provide an attachment for drill pipes that is simple and practical in construction, efficient and reliable in operation, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view of the present invention with parts broken away and shown in section;

Figure 2 is a longitudinal vertical sectional view of Figure 1, with parts of the device broken away and shown in section;

Figure 3 is a horizontal sectional view taken on line 3-3 of Figure 2;

Figure 4 is a horizontal sectional view taken on line 4-4 of Figure 2;

Figure 5 is a horizontal sectional view taken on line 5-5 of Figure 2;

Figure 6 is a horizontal sectional view taken on line 6-6 of Figure 2; and

Figure 7 is a horizontal sectional view taken on line 7-7 of Figure 2.

Referring now to the drawings in detail, wherein for the purpose of illustration, there is disclosed a preferred embodiment of the present invention, the numeral 10 represents a drill pipe hollow throughout which is removably secured to a substantially cylindrical extension 12 by means of a coupling ring 14.

Integrally formed with extension 12 adjacent its lower end is an annular ring or boss 16 provided with an inclined upper surface 18. Circumferentially spaced brackets 20 are carried by this ring and support roller bearings 22.

Journalled on extension 12 adjacent its upper end is a packing gland or collar 24 that engages the upper end of a bearing member 26 loosely embracing the lower portion of the extension. This bearing member is provided with an annular inclined inner face 28 that is spaced parallel to surface 18 of the ring, and this face 28 bears against rollers 22.

Journalled on extension 12 intermediate its lower end and below ring 16, is a bushing 30 that engages a packing gland 32 also journalled on said extension. The outer externally threaded portion of bushing 30 engageably receives the lower internally threaded portion of member 26.

Also engaged with the lower portion of member 26 is a cylindrical housing or bearing extension 34 in which is mounted a spiral vane 36 having a flanged portion 38 at one edge that is removably secured by fastening means 40 to the housing.

The lower portion of housing 34 is internally threaded to engageably receive a closing cap 42 provided with an internally threaded bore 34 for engaging the threaded shank portion 46 of a drill bit 48 having an axial liquid delivery passage through its length.

Loosely embracing a portion of the pipe 10 and the upper portion of extension 12 is a heavy pipe section 50 having its lower annular edge 52 inclined to bear on the inclined upper edge 54 of bearing member 26.

Receivably engaged at the upper end of section 50 is a closing cap 56 that loosely embraces the pipe 10 and which is disposed above the liquid level of a fluid in a well where the present invention is employed. A plurality of circumferentially spaced vertically disposed roller bearings 58, are carried by said cap and bear against pipe 10.

The outer edge of packing gland 24 is provided with circumferentially spaced notches 60 that are engaged by a suitable tool for tightening or removing the gland from engagement with bearing member 26.

Packing gland 32 is also provided with circumferentially spaced notches 62 at its outer edge which permits the insertion of a tool for removing the gland 32 from bushing 30. Should it be desirable to remove the bushing 30 from engagement with the bearing member 26, a tool is inserted in the tool receiving aperture 64 provided in the bearing member.

In practical use of the device, the same is merely slipped upwardly onto the lower end of drill pipe 10, and pipe 50 is raised on the pipe

10 to provide a space between pipe 50 and the bushing member 26, so that coupling 14 may be engaged with the lower end of the well pipe which retains the device in a correct position to the well pipe.

The drill bit 48 is then engaged with cap 42 to rotate with the well pipe 10, that is to be driven.

The pipe section 50 is of heavy durable metal to add additional weight to the lower end of the well pipe 10 so that the drill bit will tend to remain vertical when rotating and will also tend to prevent the drill from turning off its true vertical course.

A drill fluid is pumped or suitably forced through the well pipe and as the pipe is vertical gravitational force will cause the fluid to impinge on the vane 38 with great force and this fluid will follow the contours of the vane which will rotate housing 34, bushing 26 and pipe section 50. This procedure will impart a rotary motion to the drill bit.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A deep well drilling apparatus comprising a drill pipe, a hollow extension therefor, a coupling member disposed between said pipe and said extension, a casing loosely embracing said coupling member, a bearing member loosely embracing said extension and supporting the casing, a housing carried by said bearing member, and a plurality of spiral vanes mounted in said housing for imparting rotary motion to the drill upon being contacted by a fluid forced through the pipe into said housing.

2. A deep well drilling apparatus comprising a rotary drill pipe hollow throughout, a housing, means journaled on said pipe for supporting said housing, a plurality of spiral vanes mounted in said housing for imparting rotary motion to said drill and said supporting means upon being contacted by a flow of fluid forced through the pipe into said housing, and means carried by said housing for engaging a drill bit.

3. A deep well drilling apparatus comprising a drill pipe, a hollow extension removably secured to said drill pipe, a pipe section embracing adjacent portions of said drill pipe and said extension, a cap carried by said pipe section, bearings carried by said cap interposed between said pipe section and said drill pipe, a bearing member embracing said extension and supporting said pipe section, further bearings between said extension and said bearing member, a housing car-

ried by said bearing member and a plurality of spiral vanes mounted in said housing for imparting a rotary motion to said housing, said bearing member, and said pipe section upon being contacted by a fluid forced through the drill pipe and extension.

4. A deep well drilling apparatus comprising a drill pipe, a hollow extension removably secured to said drill pipe, a pipe section embracing adjacent portions of said drill pipe and said extension, a cap carried by said pipe section, bearings carried by said cap interposed between said pipe section and said drill pipe, a bearing member embracing said extension and supporting said pipe section, said bearing member having an inclined inner face, an annular ring integrally formed with said extension having an inclined upper face spaced parallel to the inclined inner face of said bearing member, further bearings interposed between said inclined faces, a housing carried by said bearing member, and a plurality of spiral vanes mounted in said housing for imparting a rotary motion to said housing, said bearing member, and said pipe section upon being contacted by a fluid forced through the drill pipe and extension.

5. A deep well drilling apparatus comprising a drill pipe, a hollow extension, means coupling said extension to said drill pipe, an annular ring integrally formed with said extension having an inclined bearing surface, a bearing member embracing the lower portion of said extension and having an outer bearing surface and an inner bearing surface, said inner bearing surface being spaced parallel to said inclined bearing surface, bearings between said inner bearing surface and said inclined bearing surface, an upper pipe section embracing said drill pipe and said coupling means, said pipe section including a lower bearing edge engaging the outer bearing surface of said member, said pipe section being slidable on said drill pipe for accessibility to said coupling means, a cap carried by the upper end of said pipe section, further bearings carried by said cap engaging said drill pipe, a housing carried by said bearing member, and a plurality of spiral vanes mounted in said housing for imparting a rotary motion to said pipe section, said housing and said bearing member upon being contacted by a fluid forced through the drill pipe and extension.

6. The combination of claim 5 wherein said bearing edge of said pipe section is inclined and the outer bearing surface of said member is inclined to engage the bearing edge.

JAMES A. HOLCOMB.
